UNITED STATES PATENT OFFICE.

CLARENCE EDGAR WILLIAMS, OF BUFFALO, NEW YORK, ASSIGNOR TO NATIONAL GYPSUM COMPANY, OF BUFFALO, NEW YORK, A CORPORATION OF DELAWARE.

BUILDING CONSTRUCTION.

Application filed November 15, 1926. Serial No. 148,441.

This invention relates to building constructions and more particularly to a method of fastening and re-enforcing sheathing.

In view of the increase in the cost of lumber and the steadily growing demand for insulation of homes, composition boards are being used as a substitute for wood sheathing. The composition boards now on the market are made of waste sugar cane, wood fiber, corn stalks and other waste vegetable matter. In addition, boards made of mineral compositions and consisting of combinations of gypsum, magnesite and other materials provided with paper facings or coverings are being used for this purpose. These boards develop certain defects which, to some extent, defeat the purpose of the sheathing through the loosening of the nails by which they are secured to the frame of the building. The object of the present invention is to provide means for stiffening the structure with a metal re-enforcing and reducing the number of nail holes through the boards.

In carrying out the invention, I provide a strip preferably formed of metal adapted to fit over the adjacent edges of two boards and provided with flanges extending over the outer surface of one of the boards and the inner surface of the other. Either one or both flanges may be nailed to the framework. The nails in the flange at the rear of the boards do not extend through the boards and any nails driven through the other flange are re-enforced by it and prevented from loosening by the metal of the flange.

The web of the strip may, or may not, be at right angles to the flanges, depending on the angle of the edges of the boards with which it is to be used. The cross section of the strip may be varied to accommodate boards of different types and I have shown several different forms of the strip in the accompanying drawings.

Referring to the drawings—

Fig. 1 is a front elevation of a portion of a wall showing the invention applied;

Fig. 2 is a vertical sectional view;

Fig. 3 is an end elevation of the meeting edges of two boards showing one form of strip in which nails are passed through the rear flange to the studding;

Fig. 4 is a similar view showing another form of strip;

Fig. 5 is a similar view showing another

form of strip in which the nails pass through both flanges;

Fig. 6 is a horizontal sectional view showing the type of washer used in the vertical rows of nails;

Fig. 7 is a detail view showing the washer before the nail is driven into the studding;

Fig. 8 is an end elevation of a strip employed in connection with sheathing boards having V shaped edges;

Fig. 9 is a similar view of a strip used with sheathing boards in which the recess is formed in the upper edge of the lower board;

Fig. 10 is a similar view of a strip used in connection with boards having curved edges, and,

Fig. 11 is a similar view of a strip used in connection with boards having tongues and grooves in their meeting edges.

Referring to the drawings, the reference numeral 1 designates the sections of the composition board which may be of any of the various types of board manufactured and sold as a substitute for sheathing. The sections of the board may be of any desired width and length. These boards are generally made four feet in width and of various lengths. In applying the sheathing to a building, it is nailed to the vertical studding, 2, which studding is placed at predetermined distances from each other. In employing the re-enforcing and connecting strip forming the subject matter of the present invention a horizontal row of the sheathing strips are first applied and before the application of the next row, a connecting strip is placed along the upper edge of the boards and the lower row. This connecting strip consists of a web, 2', adapted to be arranged over the upper edge of the board and provided with flanges 3 and 4. The front flange, 3, is a depending flange and extends over a portion of the outer face of the lower strip adjacent its upper edge. The rear flange, 4, extends upwardly in contact with the face of the studding and is secured thereto by nails, 5, driven through the flange. As the composition boards are frequently made with their edges at an angle other than a right angle to the face, the web may be arranged at a corresponding angle as shown in Fig. 2 of the drawings to fit snugly over the edge of the board.

In Figs. 3 and 4 of the drawings, I have

shown two forms of the strip in which the angle of the web to the flange varies to correspond to the angle of the edge of the board with which the strip is used in each instance. 8 As shown in these views, the boards may be secured to the studding entirely by the nails, 5, passing through the rear flange, 4, so that no nails pass through the board. When the rear flange is secured to the studding in this 10 manner, the engagement of the flange, 3, with the front of a board is sufficient to retain it in position and the lower edge of the upper board is retained in position by the arrangement of its lower portion within the 15 strip.

It is sometimes advisable, however, to nail the lower flange to the studding as well as the upper flange and in this instance, a nail, 6, may be driven through the lower flange 20 and the board as shown in Figs. 2 and 5. I have found, however, that the nail passing through the metal flange does not tend to loosen as heretofore when passed directly through the composition board. Due to the 25 presence of the metal flange, moisture is prevented from entering the nail hole and causing it to enlarge. In Fig. 5 of the drawings, I have not only shown the nail passing through the lower flange, but have also 30 shown the web at a more acute angle to the flanges.

In the construction of a building the reinforcing strips are arranged horizontally and I also find it advantageous to secure the 35 boards to the studding by vertical rows of nails. Nails, 7, are driven through the board into the studding in vertical rows as indicated in Fig. 1 of the drawings. In connection with these nails, I preferably employ 40 metal washers, 8. When the nails are driven into the board, the central portion of the washer is forced inwardly as at 9 causing the edges of the washer to tightly engage the surface of the board and prevent water 45 from getting beneath the washer and entering the nail hole.

In Fig. 8 of the drawings, I have shown a strip in which the web, 2', is substantially V shaped in cross section. This strip is 50 adapted to be used with a lower board having a V shaped projection adapted to be received in a V shaped recess on the lower edge of the upper board to form a lap joint. The web fits snugly over the edges of the 55 boards and does not interfere with the formation of the lap joint.

The form of the invention shown in Fig. 9 of the drawings is adapted to be used when the V shaped recess is on the upper edge of 60 the lower board and the projection on the lower edge of the upper board.

Fig. 10 shows a somewhat similar construction in which the strip is adapted to be used with boards having curved edges, one 65 of which is concave and the other of which

is convex. In this form the web is similarly curved.

In the form of the invention shown in Fig. 11 of the drawings, the web is substantially at right angles to the flanges, 3 and 4, but is provided with a centrally disposed rounded portion, 10. This form of strip is adapted to be used with boards having tongues and grooves on their meeting edges and the portion, 10, is shaped to correspond 75 with the shape of the tongues and grooves. The metal strips may also be arranged along the vertical edges of the boards and the vertical rows of nails, 7, driven through the flanges, 3 or 4, thus, disposing with the 80 metal washers, 8.

The metal re-enforcing strips may be of any gauge and may be provided with series of nail holes at regular intervals. I have found that when 28-30 gauge galvanized 85 iron is employed the nails may be driven through the strip and it is unnecessary to punch the nail holes in the strip prior to its application.

I claim:

1. A device for use in building construction comprising a web adapted to be arranged on the upper edge of a board, a depending flange formed on said web and extending over a portion of the front face of the board, and an upwardly extending flange arranged in the plane of the rear face of the board.

2. In a building construction, in combination with a pair of boards arranged edge to edge, a re-enforcing and stiffening member comprising a web arranged between the adjacent edges of the boards, a depending flange arranged on one edge of said web and overlying a portion of the front face of one 100 of the boards, and an upwardly extending flange arranged on the other end of the web and contacting with the rear face of the second board.

3. In a building construction, in combination with a pair of boards having inclined edges adapted to be arranged adjacent each other, a re-enforcing and stiffening member comprising a web extending between the adjacent edges of the boards, a depending 115 flange arranged on one end of said web and overlying a portion of the front face of one board, and an upwardly extending flange arranged on the other end of said web and contacting with the rear face of the second 120 board.

4. In a building construction, in combination with a pair of boards arranged edge to edge with the lower edge of the upper board inclining upwardly from its rear face and the upper edge of the lower board being similarly inclined, a re-enforcing and stiffening member comprising a web adapted to be arranged between the adjacent edges of the boards, a depending flange formed at the front of the 125

web and adapted to contact with the front face of the lower board and an upwardly extending flange formed at the back of the web and arranged in the plane of the rear faces of the boards.

5. In a building construction, in combination with a pair of boards arranged edge to edge and having interfitting tongues and grooves, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
10. In a building construction, in combination with a pair of boards arranged edge to edge, one of which is provided with a concave face and the other of which is provided with a convexly curved face, adapted to form a lap joint with the edge of the first board, a re-enforcing and stiffening member comprising a web adapted to be ar-
15. In a building construction, in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
20. In a building construction, in combination with a pair of boards arranged edge to edge, one of which is provided with a concave face and the other of which is provided with a convexly curved face, adapted to form a lap joint with the edge of the first board, a re-enforcing and stiffening member comprising a web adapted to be ar-
25. In a building construction, in combination with a pair of boards arranged edge to edge, one of which is provided with a concave face and the other of which is provided with a convexly curved face, adapted to form a lap joint with the edge of the first board, a re-enforcing and stiffening member comprising a web adapted to be ar-

ranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.

30. In a building construction in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
35. In a building construction in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
40. In a building construction in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
45. In a building construction in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.
50. In a building construction in combination with a pair of boards arranged edge to edge, one of which is provided with a V shaped recess and the other of which is provided with a V shaped projection adapted to be received in said recess and forming a lap joint, a re-enforcing and stiffening member comprising a web adapted to be arranged between the adjacent edges of the boards and shaped to fit over the edges of the boards, a depending flange arranged on one edge of said web and overlying a portion of the front face of one of the boards, and an upwardly extending flange arranged on the other edge of the web and contacting with the rear face of the second board.

In testimony whereof I affix my signature.
CLARENCE EDGAR WILLIAMS.
